UNITED STATES PATENT OFFICE.

OSCAR L. LAWSON, OF LYNN, MASSACHUSETTS.

TACK-DRIVING DEVICE.

Application filed September 14, 1923. Serial No. 662,771.

To all whom it may concern:

Be it known that I, OSCAR L. LAWSON, a subject of the King of Sweden, and a resident of Lynn, in the county of Essex, 5 and State of Massachusetts, have invented certain new and useful Improvements in Tack-Driving Devices, of which the following is a specification.

This invention relates to devices for driving tacks into the soles of boots and shoes, and has for its object the production of a device of this character in which means is provided for bending the point of the tack during the driving operation so that said point will never extend through the material.

The invention consists of a reciprocating member adapted to drive a tack, and means operable by the movement of said member 10 for curving the point of said tack while being driven.

The invention further consists in certain novel features of construction and arrangement of parts which will be understood 25 readily by reference to the description of the drawings, and to the claims to be hereinafter given.

For the purpose of illustrating the invention, one preferred form thereof is shown 30 in the drawings, this form having been found to give satisfactory and reliable results, although it is to be understood that the various instrumentalities of which the invention consists can be variously arranged 35 and organized, and that the invention is not limited to the precise arrangement and organization of the instrumentalities as herein shown and described, except as required by the scope of the appended claims.

40 Of the drawings:

Figure 1 represents a front elevation of a device embodying the principles of the present invention.

Figure 2 represents a side elevation of 45 same.

Figure 3 represents an inverted plan of the same.

Figure 4 represents a vertical section of same on line 4, 4 on Fig. 1.

50 Figure 5 represents a vertical section on line 5, 5 on Fig. 4.

Figure 6 represents a detail showing a tack clamped between the tack holding jaws and the point turning member in open position.

Figure 7 represents a similar view with the point turning member in closed position.

Figures 8 and 9 represent plans of the ends of the tack clamping jaws. 60

Figure 10 represents an elevation of a tack with the point curved after being driven, and

Figure 11 represents a sectional detail of the lower end of the tack separator. 65

Similar characters indicate like parts throughout the several figures of the drawings.

In the drawings, 10 is a casing having a tubular member or plunger 11 therein, in 70 which is disposed a cylindrical driving member 12 having a driver 13 in the lower end thereof.

The tubular member or plunger 11 has a head 14 threaded to its upper end, the outer 75 face of which is rounded so that it may be struck by the hand when it is desired to drive a tack.

The casing 10 has a pin 15 mounted therein and extending through a slot 16 in the tubular member or plunger 11 and between this pin 15 and the head 14 is positioned a spring 17 adapted to return the plunger 11 to its normal position as indicated in the drawings, after it has been moved downwardly in the casing 10 to drive a tack. As shown in the drawings, the plunger 11 is adapted to be manually operated, but it is obvious that the casing may be mounted 80 upon a machine and the plunger 11 actuated by power. 85

The upper end of the cylindrical member 12 is secured in the bottom of the tubular member or plunger 11 by means of a pin 18. 90

Loosely mounted on the cylindrical member 12 is a collar 19 having diametrically disposed ears 20 extending laterally therefrom, the downward movement of said collar 19 on the cylindrical member 12 being limited by the pin 12* extending laterally 100 from the member 12.

Mounted upon the lower end of the casing 10 is a laterally extending bracket 21 to the outer end of which is secured the inclined raceway 22 in which is disposed a plurality of tacks 23, to be driven into material such, for instance, as the sole of a boot or shoe. 105

The lower end of the raceway has a serrated portion 24 adapted to rest upon the 110

work and retain it in position while the tack is being driven.

The upper end of the raceway is provided with a device 25 adapted to engage with a loading mechanism of any well known construction, while the raceway is being filled with tacks. This loading mechanism and the means 25 for attaching it to the raceway form no part of the present invention, and therefore require no illustration or description.

Between the collar 19 and the bottom of the tubular member 12 is a spring 26 which normally retains the collar 19 in contact with the pin 12^x, but is adapted to be compressed when the collar 19 reaches its lowest position and the cylindrical member 12 moves downwardly therethrough.

The lateral pin 12^x in the lower end of this cylindrical member 12 is adapted to engage a cam face 27 on a tack separating lever 28 pivoted at 29 to the hub of the bracket 21.

The lever 28 has a finger 30 adapted to enter between the tacks in the raceway 22 and separate one from the rest and force it from the end of the raceway into the oppositely disposed grooves in the clamping jaws 31, 31^x, pivoted at 32 to the ears 20 extending outwardly from the collar 19. The entering end of the finger 30 is wedge-shaped as indicated at 32 in Fig. 11 of the drawings, and is normally within the raceway until the pin 12^x, acting upon the cam surface 27, forces it outwardly therefrom against the tension of the spring 22^x secured to the raceway 22.

The jaws 31, 31^x are held together normally by the spring 34, and have projections 34^x thereon, adapted to bear normally upon the cylindrical member 12 to limit the inward movement of said jaws toward each other, and centralize the tack 23 beneath the driver 13.

One jaw 31^x has pivoted thereto at 35 a lever 36 having at one end a lateral pin 37 adapted to engage a cam 38 on a downwardly extending bar 39 secured at 40 to the hub of the bracket 21. The pin 37 is retained in engagement with the cam 38 by means of the spring 34 one end of which is secured to the lever 36, and thus saves the double purpose of holding the jaws 31, 31^x together and also the constant contact between the pin 37 and cam 38.

The hub of the bracket 21 is preferably split and clamped to the casing 10 by the screw 41.

The lower end of the jaw 31^x has less depth than the depth of the lower end of jaw 31, and the gripping face of the jaw 31 is curved away from the axis of the driver 13 as indicated at 42.

The lever 36 has a lateral finger 43 at its lower end which extends beneath the lower end of the jaw 31^x, and when the jaws 31,

31^x are moved downwardly, the pin 37 will strike the cam 38, causing the lever 36 to be moved about its pivot 35, thereby forcing the finger 43 against the pointed end of a tack held by the jaws 31, 31^x, and in turn 70 forcing the joint of the tack against the curved face 42, thus curving said point as it is driven into the material.

The face of the finger 43 coacting with the curved face 42 of the jaw 31 is curved to fit 75 said curved face 42.

The jaws 31, 31^x are curved slightly at 44 so that when the driver 13 is forced downwardly against the head of a tack held by said jaws, it will spread the jaws 31, 31^x 80 apart, permitting the end of the driver 13 to enter between said jaws and drive the tack into the material.

This operation does not occur, however, until the cylindrical member 12, collar 19 and jaws 31, 31^x have moved downwardly together to a point where the lower end of the jaws 31, 31^x reach the upper face of the work.

Until this time, the arms 45 on the upper ends of the jaws 31, 31^x bearing against the outer wall of the hub of the bracket 21 prevent the jaws 31, 31^x from separating.

By the time the lower ends of the jaws 31, 31^x reach the work, the arms 45 will pass from contact with said hub and may then move toward each other, permitting the lower ends of the jaws to be separated by the driver 13 as it drives a tack.

When the driver 13 moves upwardly from between the jaws 31, 31^x, the spring 34 will again move the lower ends of the jaws 31, 31^x together and the arms 45 outwardly, so that the latter may again bear upon the hub of bracket 21.

When the hub 13 moves upwardly, the tack separator 28 operates to force another tack between the jaws 31, 31^x preparatory to another downward movement of the driver 13.

Preferably the adjacent walls of tack-gripping portions of the jaws 31, 31^x nearest the tack separator 28, 30 are slightly separated to permit the free admission of a tack between the gripping portions of said jaws.

When a tack is driven by a device such as is herein shown and described, the pointed end of the tack will be curved as indicated in Fig. 10, and as it enters the work, the point will continue to follow this curve so that it will be impossible for it to pass through the material.

It is obvious, therefore, that by the use of this device a shoe may be made in which the tacks used in its construction will never enter the interior of the shoe to annoy the wearer thereof.

It is believed that the operation and many advantages of the invention will be

fully apparent without further description.

Having thus described my invention, I claim:

5. 1. In a device of the class described, a casing; a reciprocating member therein; a driving member secured thereto; a collar through which said driving member is adapted to move; jaws pivotally mounted on said collar; means for feeding a tack between said jaws; means permitting said jaws to separate when the driving member is actuated; and means operable during the driving operation for curving the pointed end of the tack being driven. 70
2. In a device of the class described, a casing; a reciprocating member therein; a spring for forcing said member outwardly; a driving member secured to said reciprocating member and provided with a limiting stop; a collar loosely mounted on said driving member; a spring for normally retaining said collar against said stop; a pair of jaws pivoted to said collar; a spring normally retaining the lower ends of said jaws in contact; means for feeding a tack between said jaws; and means permitting said jaws to separate when the driving member is actuated. 80
3. In a device of the class described, a casing; a reciprocating member therein; a spring for forcing said member outwardly; a driving member secured to said reciprocating member and provided with a limiting stop; a collar loosely mounted on said driving member; a spring for normally retaining said collar against said stop; a pair of jaws pivoted to said collar; a spring normally retaining the lower ends of said jaws in contact; means for feeding a tack between said jaws; means limiting the inward movement of said jaws toward each other; and means permitting said jaws to separate when the driving member is actuated. 85
4. In a device of the class described, a casing; a reciprocating member therein; a spring for forcing said member outwardly; a driving member secured to said reciprocating member and provided with a limiting stop; a collar loosely mounted on said driving member; a spring for normally retaining said collar against said stop; a pair of jaws pivoted to said collar; a spring normally retaining the lower ends of said jaws in contact; means for feeding a tack to said jaws; projections on said jaws engaging said driving member for limiting the inward movement of said jaws toward each other; and means permitting said jaws to separate when the driving member is actuated. 90
5. In a device of the class described, a pair of pivoted jaws; means for feeding a tack between said jaws; a driving member adapted to engage said tack and drive it between said jaws into the work; and means operable during the driving operation for curving the point of the tack as it enters the work. 95
6. In a device of the class described, a pair of pivoted jaws; means for feeding a tack between said jaws; a driving member adapted to engage said tack and drive it between said jaws into the work; and a pivoted lever having a finger coacting with one of said jaws and operable during the driving operation for curving the point of the tack as it enters the work. 100
7. In a device of the class described, a pair of pivoted jaws, one of which has a curved inner face at its lower tack-gripping end; means for feeding a tack between said jaws; a driving member adapted to be moved downwardly between said jaws and drive the tack; and means on the other jaw coacting with said curved inner face for curving the point of said tack. 105
8. In a device of the class described, a pair of pivoted jaws, one of which has a curved inner face at its lower tack-gripping end; means for feeding a tack between said jaws; a driving member adapted to be moved downwardly between said jaws and drive the tack; and pivoted means on the other jaw coacting with said curved inner face for curving the point of said tack. 110
9. In a device of the class described, a casing; a driving member therein; a collar loosely mounted thereon and adapted to move therewith a limited distance and then permit the driving member to move therethrough; a pair of jaws pivoted to said collar with their gripping faces in contact; means permitting said jaws to separate when in contact with the work to permit the passage of the driver there between to drive a tack; and means coacting with one of the jaws for curving the point of the tack during the driving operation. 115
10. In a device of the class described, a casing; a driving member therein; a collar loosely mounted thereon and adapted to move therewith a limited distance and then permit the driving member to move therethrough; a pair of jaws pivoted to said collar with their gripping faces in contact; means permitting said jaws to separate when in contact with the work to permit the passage of the driver there between to drive a tack; a lever pivoted to one of said jaws and provided with a finger coacting with the other for curving the point of the tack during the driving operation. 120
11. In a device of the class described, a casing; a driving member therein; a collar loosely mounted thereon and adapted to move therewith a limited distance and then permit the driving member to move therethrough; a pair of jaws pivoted to said collar with their gripping faces in contact. 125
12. In a device of the class described, a casing; a driving member therein; a collar loosely mounted thereon and adapted to move therewith a limited distance and then permit the driving member to move therethrough; a pair of jaws pivoted to said collar with their gripping faces in contact. 130

means permitting said jaws to separate when in contact with the work to permit the passage of the driver there between to drive a tack; a lever pivoted to one of said jaws and provided with a finger coacting with the other jaw for curving the point of the tack during the driving operation, said lever having a lateral pin; and a fixed cam member with which said pin coacts during the downward movement of said jaws.

12. In a device of the class described, a casing; a bracket extending laterally therefrom; a pair of jaws adapted to grip a tack; a driving member adapted to enter between said jaws and drive the tack; a raceway for tacks supported from said bracket; a lever pivoted to said bracket and provided with

a cam face and a wedge-shaped finger extending through said raceway; a spring for normally retaining said finger in said raceway; and a pin on said driving member adapted in the movement of said driving member to coact with said cam face and move said finger outwardly from said raceway, the lower end of said raceway having a serrated work-engaging face.

Signed by me at 746 Old South Bldg., Boston, Mass., this 11th day of September, 1923.

OSCAR L. LAWSON.
